(57) **CLAIM**

The ornamental design for a thermal therapy pad, as shown and described.

DESCRIPTION

FIG. 1 is a front perspective view of a preferred embodiment of the thermal therapy pad according to the present design, illustrating the pad applied to a wearer's ankle;

FIG. 2 is a front elevational view of the thermal therapy pad of FIG. 1;

FIG. 3 is a rear elevational view of the thermal therapy pad of FIG. 1;

FIG. 4 is a left-side elevational view of the thermal therapy pad of FIG. 1;

FIG. 5 is a right-side elevational view of the thermal therapy pad of FIG. 1;

FIG. 6 is a top plan view of the thermal therapy pad of FIG. 1; and,

FIG. 7 is a bottom plan view of the thermal therapy pad of FIG. 1.

Phantom lining, where used, is for illustrative purposes only and is not intended to limit the claimed design to the features shown in phantom.
